(57) **CLAIM**

The ornamental design for a blind slat as shown and described.

DESCRIPTION

FIG. 1 is a front, right-side and top perspective view of a blind slat showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged fragmentary left side elevational view thereof.

The design is shown with a symbolic break in its length. The appearance of any portion between the break lines forms no part of the claimed design.
